UNITED STATES PATENT OFFICE

2,105,242

PAD FOR USE WITH HORSESHOES

Bertram Parrott Gray, Birmingham, England

Application October 28, 1936, Serial No. 108,114
In Great Britain November 20, 1935

12 Claims. (Cl. 168—14)

This invention relates to pads for use with horseshoes and primarily concerns pads of the kind which can be applied to and detached from the shoe, whilst the latter is secured to the horse's foot and without affecting the shoe fastenings.

In my prior Patent No. 1,911,187, retaining spring arms secured to or provided on the pad were adapted for detachable engagement with the sides of the shoe in an adjustable manner, but it was not easy to attach the pad securely to shoes of different sizes and in some cases the effectiveness of the retaining spring arms depended upon the degree of accuracy with which the sides of the pad had been shaped to fit the particular size of shoe.

The object of the present invention is to provide a generally improved construction which will be more readily applicable to shoes of different sizes.

20 Referring to the drawings:—

Figure 1 is a plan view illustrating one application of the present invention.

Figure 2 shows separated parts of the construction shown in Figure 1.

25 Figure 3 is a sectional elevation of same.

Figure 4 is a plan view of a modification.

Figure 5 shows the same in sectional elevation.

Figure 6 is a perspective view of a part of the retaining device incorporated in Figure 4.

30 The construction illustrated in Figures 1 and 2 includes a pad proper 8 of rubber or other suitable material having a carrier plate 9 of thin metal bent over at its edges 10 to engage in grooves or recesses 11 in the sides of the pad, the carrier plate projecting beyond the ends of the pad to provide flanges 12 for engagement with the sides 13 of the horseshoe.

The means for retaining the pad in position on the horseshoe include a strip metal member 40 14 preferably formed from spring material, this member being separable from the pad and its carrier plate and adapted for detachable engagement both with the pad and with the shoe.

45 The strip has an integral lug 15 bent to project at right angles to the width of the strip for engagement between the upper surface of the carrier plate and the under surface of the horse's foot when the pad is in position, the main portion of the strip extending transversely across the foot between the inner surfaces of the two sides 13 of the shoe.

50 The strip is curved or bowed to form two spring arms 16 each of which has at its projecting end an outwardly bent part 17 for engagement in a

notch or recess 18 in the inner face of the corresponding side 13 of the shoe.

Adjacent the end 17 each spring arm has an integral lug 19 bent at right angles to the width of the strip to engage between the upper surface 5 of the shoe and the under surface of the horse's foot as shown in Figure 3.

A transverse notch 1 is formed substantially centrally in the strip and at the position of the lug 15 to assist the spring action and increase 10 the flexibility of the strip so as to facilitate application to the shoe.

With this construction the retaining member can be separated from the pad whilst the latter is in position and the engagement of this member with the shoe is independent of the engagement between the latter and the pad, being also independent of the length of the pad.

The projection 15 can readily be slipped between the carrier plate and the underside of the 20 foot after which the ends of the arms 16 can be sprung into engagement with the recesses or notches 18.

When in position the retaining member fits snugly along the pad with the arms 16 extending 25 substantially parallel to the inner vertical faces of the arms 13 of the shoe and the lugs 15 and 19 locate the retaining member upon the pad and the shoe and prevent any displacement in normal use.

A standard pad can be provided for shoes of 30 different sizes, and the retaining member can readily be adapted to fit shoes of different sizes, or alternatively, a separate retaining member may be provided for each size of shoe.

With this construction extreme accuracy in the shaping of the pad or the retaining member so as to adapt either of these for engagement with shoes of different sizes is unnecessary and the retaining member is of extremely simple 40 construction and can readily be shortened where necessary to engage with the sides of the shoe.

In constructions where the pad itself has to be cut down to fit the size of the shoe, it is unnecessary to shape the pad accurately to fit the 45 sides of the shoe, since the retaining member engages with the shoe independently of the length of the pad.

In the modified construction illustrated in Figures 4 to 6 the retaining member comprises two 50 portions 20 of similar shape but opposite hand connected together by a helically coiled spring 21.

Each part 20 is formed from sheet metal with a strip adapted to fit along a portion of the side 55 of the pad and with an integral spring arm 23

with outwardly bent end 24 and integral projection 25 of construction similar to the parts above described with reference to Figures 1 to 3.

In addition each part 20 has an arm 26 bent 5 to engage between the carrier plate and the horse's foot with a further arm 27 projecting at right angles to the arm 26 and adapted to extend transversely across the foot substantially parallel to the length of the pad.

10 The arms 27 of the two parts project towards one another and engage one into each end of the helically coiled spring 21, which latter thus forms a resilient connection between the two parts of the retaining device and presses these 15 parts away from one another so as to engage the ends 24 firmly in the notches 18.

The arms 27 are cranked out of the plane of the part fitting against the side of the pad to provide space for the accommodation of the 20 spring 21 as will be seen from Figure 4.

Each arm 27 has projecting lugs 28 adapted 25 to engage between the coils of the spring to provide a positive connection between the latter and the arms 27 and this engagement is also an adjustable one and the effective length of the connection between the two parts 20 can be varied by rotating one or both parts relative to the spring to turn the projections 28 around different coils of the spring.

30 Each part 20 has a further arm or lug 29 bent to extend substantially parallel to the arm 26 and adapted for engagement beneath the bent-over edge 10 of the carrier plate so that when the retaining member is in position it is located 35 positively upon the pad by the engagement of the two arms 26 and 29 one on either side of the carrier plate as is shown in Figure 5.

The retaining device can be applied whilst the 40 pad is in position by engaging the arms 26 and 29 of each part 20 with the carrier plate and then springing the arms 23 of the two parts of the retaining device into engagement with the notches 18 as described with reference to Figures 1 to 3.

By suitable adjustment of the connection 45 between the spring 21 and the arms 27 of the two parts the spring 21 can be compressed during the application of the retaining device sufficiently to ensure that the force of the spring holds the two parts of the retaining device in engagement 50 with the shoe to prevent detachment of the pad until the retaining device has been released.

By selection of a spring 21 of suitable length and strength the retaining device can be adapted 55 for application to a shoe of any one of a number of sizes with a suitable spring effect for any particular size.

With this arrangement the retaining member 60 can be separated from the pad, whilst the latter is in position and can readily be adjusted to fit shoes of different sizes without necessitating alterations in the parts of the member other than adjusting the effective length of the spring as described above.

It is unnecessary to observe extreme accuracy 65 in shaping either the pad or the retaining member to fit the sides of the shoe and the effectiveness of the engagement between the retaining member and the shoe is independent of the engagement between the latter and the pad or of the length of the pad proper.

In order to make the retaining strip flexible in a vertical direction so that it can bend up and down with the pad, it may be weakened by slits, notches or recesses in its edges in suitable positions, such as adjacent the lugs.

What I claim then is:—

1. A horseshoe pad including a pad member capable of application to, or removal from, the shoe without removing the latter and a retaining member for securing said pad member detachably to said shoe, end parts of said retaining member adapted for releasable engagement with the shoe and a part adapted to abut against the front of the pad member in a detachable manner to enable removal or replacement of said retaining means independently of the removal or replacement of the pad member. 5

2. A horseshoe pad including a pad member capable of application to, or removal from, the shoe without removing the latter and retaining means for securing said pad member detachably to said shoe, said means including a strip metal member, end parts of said member adapted for releasable engagement with the shoe and a central part of said member adapted to abut along 20 the front of the pad member and also to engage above the pad member in a detachable manner to enable removal or replacement of said retaining means independently of the removal or replacement of the pad member. 25

3. A horseshoe pad including a pad member capable of application to, or removal from, the shoe without removing the latter and retaining means for securing said pad member detachably to said shoe, said means including a bowed metal 30 strip, a spring arm at each end of said strip, the end of each arm being shaped to engage detachably in a notch in the side of the shoe, a part of said strip adapted to abut against the front of said pad member and a projection on said strip 35 adapted for detachable engagement above the pad member to enable removal or replacement of said retaining means independently of the removal or replacement of the pad member.

4. A horseshoe pad including a pad member 40 capable of application to, or removal from, the shoe without removing the latter, a carrier plate for said pad member, and retaining means for securing said pad member detachably to said shoe, said means including a strip metal member, parts of said member adapted for releasable 45 engagement with the shoe and a part of said member adapted to abut against the carrier plate along the front of said pad member and also to engage above the carrier plate in a 50 detachable manner to enable removal or replacement of said retaining means independently of the removal or replacement of the pad member.

5. A horseshoe pad including a pad member capable of application to, or removal from, the 55 shoe without removing the latter, a carrier plate for said pad member and retaining means for securing said pad member detachably to said shoe, said means including a bowed metal strip, a spring arm at each end of said strip, the end of 60 each arm being shaped to engage detachably in a notch in the side of the shoe, a part of said strip adapted to abut the carrier plate along the front of said pad member and a projection on said strip adapted to engage detachably above 65 the carrier plate to enable removal or replacement of said retaining means independently of the removal or replacement of the pad member.

6. A horseshoe pad including a pad member capable of application to, or removal from, the 70 shoe without removing the latter and retaining means for securing said pad member detachably to said shoe, said means including two metal members, an integral spring arm on each of said members, the end of said arm being shaped to 75

engage detachably in a notch in the side of the shoe, resilient means connecting said members a part of each member adapted to abut against the front of the pad member and a projection on each member adapted for detachable engagement above the pad member to enable removal or replacement of said retaining means independently of the removal or replacement of the pad member.

5. A horseshoe pad including a pad member capable of application to, or removal from, the shoe without removing the latter, a carrier plate for said pad member and retaining means for securing said pad member detachably to said shoe, said means including two metal members, 10 an integral spring arm on each of said members, the end of said arm being shaped to engage detachably in a notch in the side of the shoe, a spring connecting said members resiliently, a part on each member adapted to abut against the carrier plate at the front of said pad member and a projection on each member adapted to engage detachably above the carrier plate to enable removal or replacement of said retaining means independently of the removal or replacement of 15 the pad member.

7. A horseshoe pad including a pad member capable of application to, or removal from, the shoe without removing the latter and retaining means for securing said pad member detachably 20 to said shoe, said means including two metal members, an integral spring arm on each of said members, the end of said arm being shaped to engage detachably in a notch in the side of the shoe, projecting arms on said members, a coiled 25 spring connecting said arms, lugs on said arms engaging adjustably between the coils of said spring and a projection on each member adapted for detachable engagement with the pad member to enable removal or replacement of said retaining means independently of the removal or replacement of the pad member.

8. A horseshoe pad including a pad member capable of application to, or removal from, the shoe without removing the latter, a carrier plate 30 for said pad member and retaining means for securing said pad member detachably to said shoe, said means including two metal members, an integral 35 spring arm on each of said members, the end of said arm being shaped to engage detachably in a notch in the side of the shoe, resilient means connecting said members, a part of each member adapted to abut against the front of the pad member and a projection on each member adapted for detachable engagement above the pad member to enable removal or replacement of said retaining means independently of the removal or replacement of the pad member.

9. A horseshoe pad including a pad member capable of application to, or removal from, the shoe without removing the latter, a carrier plate

45 for said pad member and retaining means for securing said pad member detachably to said shoe, said means including two metal members, an in-

tegral spring arm on each of said members, the end of said arm being shaped to engage detachably in a notch in the side of the shoe, projecting arms on said members, a coiled spring connecting said arms, lugs on said arms engaging adjustably 5 between the coils of said spring and a pair of spaced projections on each member to engage detachably one on either side of said carrier plate to enable removal or replacement of said retaining means independently of the removal or replacement of the pad member.

10. Retaining means for a horseshoe pad including a bowed metal strip, a spring arm at each end of said strip, the end of each arm being shaped to engage detachably in a notch in the side 10 of the shoe, a part of said strip adapted to abut against the front of said pad member and a projection on said strip adapted for detachable engagement above the pad member to enable removal or replacement of said retaining means independently of the removal or replacement of the pad member.

11. Retaining means for a horseshoe pad including two metal members, an integral spring arm on each of said members, the end of said 15 arm being shaped to engage detachably in a notch in the side of the shoe, resilient means connecting said members, a part of each member adapted to abut against the front of the pad member and a projection on each member adapted for detachable engagement above the pad member to enable removal or replacement of said retaining means independently of the removal or replacement of the pad member.

12. Retaining means for a horseshoe pad including two metal members, an integral spring arm on each of said members, the end of said arm being shaped to engage detachably in a notch in the side of the shoe, projecting arms on said members, a coiled spring connecting said arms, 35 lugs on said arms engaging adjustably between the coils of said spring and a projection on each member adapted for detachable engagement with the pad member to enable removal or replacement of said retaining means independently of the removal or replacement of the pad member.

BERTRAM PARROTT GRAY.
